(57) **CLAIM**

The ornamental design for a medical gown, as shown and described.

DESCRIPTION

FIG. 1 is a perspective view of the medical gown with access flaps in an open position in full lines and an outline of the human body in broken lines representing environmental subject matter being for illustrative purposes only and forming no part of the claimed invention.

FIG. 2 is a front elevational view of the medical gown.

FIG. 3 is a rear elevational view thereof.

FIG. 4 is a right side elevational view thereof.

FIG. 5 is a left side elevational view thereof.

FIG. 6 is a top plan view of the medical gown; and,

FIG. 7 is a bottom plan view thereof.

The broken lines shown around the periphery of the openings in FIG. 1 are understood to represent stitching.
